SINK ATTACHED DISHWASHER UNIT

George William Walker, Bloomfield Hills, Mich., assignor to Gerity-Michigan Corporation, Adrian, Mich., a corporation of Michigan

Application January 13, 1956, Serial No. 39,756

Term of patent 14 years

(Cl. D91—3)

Fig. 1 is a front elevational view of a sink attached dishwasher unit embodying my new design;

Fig. 2 is a top plan view thereof;

Fig. 3 is a side elevation taken from the right side of Fig. 1; and

Fig. 4 is a side elevation taken from the left side of Fig. 1.

I claim:

The ornamental design for a sink attached dishwasher unit, substantially as shown.
